UNITED STATES PATENT OFFICE.

EDWARD S. SAVAGE, OF ROCHESTER, NEW YORK.

TOY.

1,259,782.

Specification of Letters Patent. Patented Mar. 19, 1918.

Application filed December 24, 1915, Serial No. 68,494. Renewed August 13, 1917. Serial No. 186,057.

To all whom it may concern:

Be it known that I, EDWARD S. SAVAGE, of Rochester, in the county of Monroe and State of New York, have invented certain new and useful Improvements in Toys; and I do hereby declare the following to be a full, clear, and exact description of the same, reference being had to the accompanying drawings, forming a part of this specification, and to the reference-numerals marked thereon.

My present invention relates to toys and more particularly to dolls and other forms simulating living or fanciful objects and it has for its object to provide a simple, cheap and efficient flexible joint between parts of such dolls or figures that it is desired to render relatively adjustable in lateral directions, which joint will be durable and slightly and, through being less bulky than joints of types heretofore used and for other reasons, will constitute a better imitation of the joints of living things. A further object of the invention is to provide a structure that may be easily and safely contorted to closely imitate the behavior of lithe and supple animate bodies such as those of fish, snakes, etc. To these and other ends the invention resides in certain improvements and combinations of parts all as will be hereinafter more fully described, the novel features being pointed out in the claims at the end of the specification.

In the drawings:

Fig. 1 is an elevation of a doll figure constructed in accordance with and illustrating one embodiment of my invention;

Fig. 2 is a longitudinal sectional view thereof, partly in elevation;

Figs. 3 and 4 are detail sections of modified forms of joints embodying features of my invention, and

Fig. 5 is a detail view of a portion of a strip of material entering into the construction of the doll shown.

Similar reference numerals throughout the several figures indicate the same parts.

In the present embodiment of the invention, I have illustrated a toy figure representing a mermaid. It consists of a body portion 1, a tail portion 2, an intermediate

connecting portion indicated generally at 3, a head 4, arm sections 5, hand sections 6 and elbow, shoulder and neck joints 7, 8 and 9, respectively. The fish-like portion of 55 the mermaid's body will first be described.

The body 1 may be made of wood or any suitable preferably solid material. The tail 2 is preferably a metal casting or, at any rate, it is made as heavy as possible proportionately to its size. Between these two terminal portions is the flexible portion 3 which I make of a soft, light, compressible and expansible material that, in the present instance, is circular in cross section. I contemplate the use of felt in this capacity and construct the portion 3 of a plurality of laminations 10, the successive superposed felt disks that constitute it being of progressively increasing or decreasing diameters to produce the proper shape and having their approximate faces glued or cemented together. The disk at one end is secured to the body 1 and that at the other end to the tail 2. Extending centrally 70 through the three members 1, 2 and 3 is a flexible but non-elastic core piece 11. I prefer to form this core piece of one or more strands of soft iron wire which can be easily and repeatedly bent without breaking and which has a tendency to remain in distorted positions. One end of this wire is anchored in the tail piece 2 as shown at 12 and is preferably hooked, cast or otherwise embedded in the material thereof, while the 85 other end extends into the body 1 and in the present instance, I have shown the same wire extended through to the head 4 in which latter its terminal is anchored in a cement body 13. This permits the same wire 90 to be utilized for the neck joint 9 to be later referred to.

The portion 3 may be suitably covered with fabric or other yielding or expansible material and in the present instance, I prefer to form this covering in a continuous manner by winding about it a strip of material of the nature shown in Fig. 5 so that the convolutions overlap and by securing such overlapping portions together with 100 glue. One edge of the strip 14 is made straight for this purpose while the other

edge is scalloped to produce flexible tongues 15 simulating the scales of a fish.

It will be readily understood from the foregoing that the terminal portions 1 and 5 2 may be bent back and forth into different relative positions, the intermediate portion 3 yielding laterally in a graceful curve and the non-elastic core piece 11 serving to both hold the parts together and to retain them 10 in the distorted positions. As the bend is made, the felt material in the larger arc beyond the curve of the central wire is expanded and that on the shorter arcs within the curve of the central wire is compressed. 15 These strains to which the laminated material is subjected are not sufficient, however, to disrupt the fibers of which it is composed and its texture remains unimpaired though repeated reversals in the direction of movement 20 may alternately subject it to expansion and contraction. The covering material 14 assists by acting as a binder and both the inside and outside external surfaces at the bend assume a symmetrical curve 25 without any tendency toward flattening.

The particular doll figure illustrated is capable of maintaining itself in the partially erect position shown in Fig. 1. In this position, the intermediate fish-like portion 3 30 serves as a support in contact with the ground line for the body 2, by virtue of the fact that the tail portion 2, being relatively heavy, acts as a counterweight at the other end. Though the portion 3 may be and 35 probably is laterally rounded also, it is prevented from rolling over in that plane by the laterally disposed fin portions 16 that take a wide contact.

The elbow, shoulder and neck joints 7, 8 40 and 9, before referred to, may be similarly constituted of laminated felt and as previously mentioned, the same core piece 11 that extends through the portion 3 may be used also for the neck 9. Similarly, a single 45 core wire 17 suffices for the two joints in both arms, the extremities being anchored in cement bodies 18 in the respective hand pieces 6 which latter are solid as are the arm sections 5. In the case of these joints, 50 instead of the scale covering before described, I may use a smooth covering 19 of an extensible fabric that will stretch over the round of the joints as the bend is made. This fabric covering is glued to the solid 55 parts such as the parts 1, 5, 6 and 4. The symmetrical curves of the bends at the joints that I obtain through my invention are well illustrated in Fig. 2.

The joints shown in Fig. 2 are all universal joints, that is, they permit a bend to be made in any lateral direction. If a one-way joint is desired, such as that of the elbow or knee, the core piece may be formed of a flat metal ribbon as shown at 20 in Fig. 4 that

can be bent only in one plane which is that 65 at right angles to its own plane, and further, the terminal portions 5 and 6 at each side of the joint may have their adjacent ends arranged so close together as at 21 that they permit no substantial compression of 70 the felt at that side while permitting expansion and be tapered off at the other side as shown at 22 to allow for substantial compression of the felt.

In Fig. 3, two flat core blades 23 are anchored 75 in cement bodies 24 in the terminal pieces 5 and 6 and are pivoted together at 25 at the center of the laminated portion 10 to turn in a definite plane but in either direction in that plane. 80

I claim as my invention:

1. In a toy, the combination with a body portion, a weighted portion and a laterally flexible intermediate supporting portion upon which the toy is adapted to rest, the 85 weighted portion acting as a counter weight for the body portion.

2. In a toy, the combination with a body portion, a laterally flexible intermediate supporting portion and a weighted terminal 90 portion adapted to counterweight the body portion, the intermediate portion being adapted to retain the different positions to which it is adjusted under the weight of the body portion.

3. In a toy, the combination with a body portion, a weighted portion and a laterally flexible intermediate supporting portion of substantially circular cross section, the weighted portion being adapted to act as a 100 counter weight for the body portion and being provided with lateral extensions to prevent lateral rocking movement of the intermediate portion.

4. A flexible joint for toys comprising two 105 terminal portions and a laterally flexible intermediate connecting portion composed of a plurality of transversely disposed laminations of expandible and compressible material.

5. A flexible joint for toys comprising two terminal portions and a laterally flexible intermediate connecting portion composed of a plurality of transversely disposed laminations of felt.

6. A flexible joint for toys comprising two terminal portions and a laterally flexible intermediate connecting portion composed of a plurality of transversely disposed laminations of expandible and compressible material and an expandible covering secured to the terminal portions.

7. A flexible joint for toys comprising two terminal portions, a laterally flexible intermediate connecting portion composed of a 125 plurality of transversely disposed laminations of expandible and compressible material and a core piece of flexible but non-

elastic material anchored in the terminal portions and extending through the connecting portion.

8. A flexible joint for toys comprising two terminal portions, a laterally flexible intermediate connecting portion composed of a plurality of transversely disposed laminations of felt and a soft iron wire constitut-

ing a core piece anchored in the terminal portions and extending through the connecting portion.

EDWARD S. SAVAGE.
